UNITED STATES PATENT OFFICE.

ROBERT N. PRESTON, OF COLDWATER, MICHIGAN.

AUXILIARY AIR-VALVE FOR INTERNAL-COMBUSTION ENGINES.

1,174,897.

Specification of Letters Patent.

Patented Mar. 7, 1916.

Application filed April 20, 1915. Serial No. 22,686.

To all whom it may concern:

Be it known that I, ROBERT N. PRESTON, a citizen of the United States, residing at Coldwater, in the county of Branch and State of Michigan, have invented new and useful Improvements in Auxiliary Air-Valves for Internal-Combustion Engines, of which the following is a specification.

This invention relates to auxiliary air valves for internal combustion engines, the object in view being to provide an air inlet valve located between the carbureter and engine and controlled by the throttle valve of the carbureter in accordance with the position of said throttle valve, the degree of opening of the throttle valve automatically regulating the volume of air admitted through said auxiliary valve into the mixture after leaving the carbureter.

20 A further object of the invention is to provide a valve of the class referred to which by reason of its construction is adapted to be easily associated with the intake pipe of an internal combustion engine in an expeditious manner and without threading said intake pipe or modifying the same further than to drill through the intake pipe.

With the above and other objects in view, 30 the invention consists in the novel construction, combination and arrangement of parts, as herein described, illustrated and claimed.

In the accompanying drawings: Figure 1 is a side elevation conventionally showing 35 an internal combustion engine, carbureter, intake pipe and manifold, and illustrating the auxiliary air valve of this invention applied to the intake pipe and controlled by the throttle valve of the carbureter. Fig. 40 2 is an enlarged section taken diametrically of the auxiliary air valve and also showing a portion of the intake pipe in section.

Referring to the drawings A generally designates an internal combustion engine, 1 45 the intake pipe thereof and 2 the carbureter.

3 designates the throttle valve lever by means of which the usual throttle valve of the carbureter is opened and closed to an extent commensurate with the speed required of the engine.

In carrying out the present invention, the intake pipe 1 is drilled or bored to provide oppositely arranged holes 4 and 5 through which the auxiliary air valve of this invention, and which is designated generally at B, is introduced as shown in Fig. 2. The

valve comprises an outer tube or casing 6 and an inner partially rotatable tube 7 fitting within the outer tube 6 and provided at one end with a flange 8 which engages the corresponding extremity of the outer tube 6 thereby preventing the accidental withdrawal of the tube 7 from the tube 6.

The outer tube or casing 6 is threaded at 9 to receive an internally threaded cap 10 which screws upon the end of the casing 6 and has its inner end shaped to conform to the curvature of the intake pipe 1 in order to form an air tight joint therewith. The casing 6 is also threaded at its opposite end 11 to receive a lock nut 12 which screws against the side of the intake pipe 1 opposite the cap 10, thereby locking the outer casing 6 in fixed and air tight relation to the intake pipe 1. The casing 6 is 75 provided with a plurality of air inlet holes 13 and the inner tube 7 is provided with a corresponding series of air inlet holes 14 adapted to register with the holes 13 more or less as the inner tube 7 is slowly revolved. Adjustably secured to the projecting extremity of the inner tube 7 is an operating arm or lever 15 having at one end a collar 16 which encircles the tube 7 and carries a binding screw 17 by means of 85 which the proper adjustment of the inner tube 7 may be effected in relation to the position of the throttle valve of the carbureter.

18 designates a connecting rod attached at 90 one end to the lever 15 and at the other end to the throttle valve lever 3 so that as the throttle is gradually opened or closed, the tube 7 is correspondingly turned in one direction or the other to admit air in proper 95 proportion to the degree of opening of the throttle valve and in accordance with the demands of the engine under varying piston speed.

By means of the invention above described 100 it is only necessary to bore a hole diametrically through opposite walls of the intake pipe and then insert the inner and outer tubes of the valve and lock the outer tube in place by means of the members 10 and 105 12. The rod 18 is then connected to the throttle valve lever 3 and by means of the binding screw 17, the tube 7 is adjusted to bring the holes 14 thereof into the proper relation to the holes 13 of the casing 6. 110 Under low engine speed, the auxiliary air valve B is practically closed so as not to

admit any air thus producing a rich mixture particularly adapted for starting the engine and maintaining the same when turning at a comparatively low rate of speed.

- 5 As the throttle valve is gradually opened to increase the speed of the engine, the auxiliary air valve is simultaneously opened proportionately. Thus a comparatively perfect mixture is always supplied to the engine in accordance with the speed at which
- 10 the engine is running.

What I claim is:—

The combination with the intake pipe of an internal combustion engine formed with diametrically opposite holes, of an auxiliary air valve comprising an outer tube or casing inserted through said holes in the intake pipe, a cap threaded on one end of said outer casing closing said end and bearing

against the intake pipe, a nut threaded on 20 said outer casing and bearing against the opposite side of the intake pipe, an inner tubular member mounted to turn within said outer casing, said tubular member and outer casing being formed with holes 25 adapted to be moved into and out of register, an operating arm for said inside tubular member, a connection between said lever and the throttle lever of the carbureter, and means for adjusting said inner 30 tubular member in relation to said outer casing.

In testimony whereof I affix my signature in presence of two witnesses.

ROBERT N. PRESTON.
